UNITED STATES PATENT OFFICE

2,535,586

HOLDER FOR BULBS

Stanley M. McElroy, Smithfield, Pa.

Application April 22, 1948, Serial No. 22,539

1 Claim. (Cl. 248—200)

1

This invention relates to holders for light bulbs and particularly the sealed beam or spotlight lamp used on industrial motor vehicles such as power shovels, cranes, conveyors or the like where the light bulb is subject to the vibration of the vehicle.

A primary object of the invention is to provide a holder for supporting the weight of a bulb and at the same time relieving the socket from any strain whatever, such strain generally occurring during the vibrations of the vehicle when in operation, usually damaging the socket and shortening the life of a bulb considerably.

Another object of the invention is to provide means whereby the spotlight is supported in a fixed manner on the vehicle or is suspended from a suitable means when it becomes necessary.

Another object of the invention is to provide a clamp support that will enable it to assume any angle of inclination and thereby make possible focusing of the light in any direction and also provide means that will be adjustable to receive bulbs of various diameters.

And another object of the invention is to support a bulb in such manner that the socket for the bulb is relieved of any holding function and merely carries the current for the lamp.

The invention accordingly comprises the features of construction, combinations of elements and arrangement of parts, which are exemplified in the description hereinafter in connection with the accompanying drawings, and the scope of the application of which will be indicated in the following claim.

In the accompanying drawings, in which is illustrated one of various possible embodiments,

Figure 1 is a side elevation of the supporting bracket and lamp in position on a motor vehicle;

Figure 2 is a side elevation, in enlarged scale of the spotlight support, parts of it shown in section for purposes of illustration;

Figure 3 is a rear view of the invention and as taken substantially on the line 3—3 of Figure 1;

Figure 4 is a perspective view of the clamping bracket of the invention, and

Figure 5 is an exploded view of a spotlight and the current carrying means therefore.

In many commercial uses, it becomes necessary to provide light means to illuminate a work. As a result, spotlights are generally secured to a fender of the vehicle or in some other manner to effect this purpose. However, due to the vibrations of the vehicle, and also due to the fact that the support for the light is applied to the current carrying means as well, frequent damage

2

will occur and the light bulb has a considerably short life. In order to relieve the socket of such strain, the present invention has been devised.

Referring to the figures, a support of the invention is indicated generally by the numeral 10 and is shown in Figure 1 mounted on the front fender 12 of a tractor or some other vehicle 13.

The manner of mounting a spotlight and supporting it is clearly illustrated in Figures 2 and 3 and the device 10 consists of a support member 15 and a clamping member 14. Attention is directed to Figure 5, where the spotlight 16 includes a neck portion 18 terminating in a socket receiving threaded end 20. A suitable socket 22 is internally threaded, not shown, and includes the usual current carrying means 24. In use, socket 22 is mounted by the threaded connection on neck 18 on extension 20. In order to avoid any undue strain on the current carrying means 24, the clamp 14 is adapted to seat and be retained on neck 18 exclusively.

In Figure 4 is shown one embodiment of the clamp and support member 14 and consists of a tubular body 26 tapering slightly at its rear portion 28. Body 26 is split in the form of an elongated notch 30 from the front end thereof and extending rearwardly for a short distance. This length will be long enough to permit tension on the neck of bulb 16 and generally will not extend beyond neck 18. At the point where notch 30 terminates in its rearmost extreme, a transverse semi-circular slit 32 is formed on body 26. A pair of ears 34 and 36 depend from, as by welding or other similar means, the clamp means

38. Bracket 34 is of somewhat wider diameter than bracket 36 and includes a recess 40 for a purpose soon to appear. A medial depending bracket 42 apertured at 44 is secured to body 26. Bracket 42 is adapted to seat in support 15 with in the bifurcated space 46 of vertical pipe 48, pipe 48 being threaded at the lower extremity 50 to seat in a nipple 52 integral with a plate or attaching flange 54. Flange 54 is suitably apertured, not shown, for rigid retention on a level support. Pipe 48 is apertured in alignment with aperture 44 and receives therethrough a headed screw 56 and is retained in locked position by locking nut 58. Thus, when it is desired to adjust the angle of the spotlight 16, screw 56 is loosened slightly, the desired angle assumed, after which it is again tightened into non-moving retention.

Clamping members 38 are seated on neck 18. see Figure 2, after which ears 34 and 36 are tensioned toward each other by means of a headed

bolt 60 extending through suitable apertures 62, a locking nut 64 received in notch 40 retaining the clamping means in locked position. A suitable compression spring 66 is mounted on nut 69 and urges against the clamping force of nut 60. Tubular body 26 is of sufficient length to sheath socket 22 without being supported thereon, thereby relieving socket 22 of any such function and retaining the entire supporting member by neck 18 on bulb 16. Suitable current carrying cables 68 terminate in socket 22.

As is illustrated in Figures 1 and 3, clamp 14 may be slightly modified by providing a vertical ear 70 mounted on the upper portion thereof and including a suitable hole or opening 72 whereby the device may be suspended from a support if it is so desired.

In use, screw 60 is loosened to permit clamp members 38 to be seated on neck 18, and the device is either retained in rigid support by means of clamping plate 54, or is suspended from member 70 as may be desired. While the retaining bolts may be of any suitable construction, it is generally preferred to have them made of brass, since these have been found to be best resistant to weather conditions. As is self-evident, spring 66 assists in the spreading action of ear 38 to permit ready removal from a spotlight.

As many modifications of the embodiments above illustrated might be made without departing from the spirit or scope of the invention, and it is intended that the above description and accompanying drawings as claimed shall be in-

terpreted as illustrative and not in a limiting sense.

Having described the invention, what is claimed as new is:

5 In a spotlight having a neck portion and a socket member carried by the neck portion; an adjustable holder comprising a tubular member having one portion embracing the neck portion and another portion embracing the socket member, a longitudinal slit in said tubular member extending only through that portion of the latter which embraces the neck portion of the spot light, a transversely extending slit in said tubular member adjacent the closed end of said first-mentioned slit, an apertured bracket depending from that portion of said tubular member which embraces the socket member and adapted to be pivoted to a support, a pair of opposed apertured ears depending from that portion of said tubular member embracing said neck portion and adjacent said first-mentioned slit, and a resiliently urged locking pin extending through said ears.
